UNITED STATES PATENT OFFICE.

ROBERT RICHARDSON TURNER, OF WEST MIDDLESEX, PENNSYLVANIA.

MACHINE FOR ROLLING COUPLING-PINS.

SPECIFICATION forming part of Letters Patent No. 291,110, dated January 1, 1884.

Application filed March 10, 1883. (No model.)

To all whom it may concern:

Be it known that I, ROBERT RICHARDSON TURNER, of West Middlesex, in the county of Mercer and State of Pennsylvania, have invented certain Improvements in Machines for Rolling Coupling-Pins for Cars, of which the following is a specification.

The aim of this invention is to provide an inexpensive means for manufacturing coupling-pins for use in railway-cars with rapidity and uniformity; and to this end it consists, essentially, in a pair of co-operating grooved rolls provided with dies of such shape that round iron rods passed between the rolls will be divided by said dies into pins of suitable length, and the heads and points formed upon said pins at the same operation.

Referring to the accompanying drawings, Figure 1 is a rear elevation of my machine. Fig. 2 is a vertical section of the same on the line *x*-*x*. Fig. 3 is a perspective view of one of the finished pins.

A represents a strong rigid frame, and B C two co-operating rolls, having their journals mounted in suitable bearings in said frame and connected by gear-wheels D and E, by which the two rolls are caused to move with equal surface-speeds. The rolls are provided with corresponding grooves, *a* and *b*, of a semi-circular cross-section, for the purpose of reducing the iron to the form of round rods of a diameter equal to that of the bodies of the required pins. The rolls are further provided at one end with semicircular grooves *c*, of the same diameter as the others, but each provided with two dies, *d*, located diametrically opposite each other. The dies *d* of the two rolls are alike in form, and the parts are arranged in such manner that as the rolls are revolved the dies upon one are brought in succession directly opposite or in register with those upon the other. The pins to be produced are of the form represented in Fig. 3, having a cylindrical body with one end flattened and extended laterally beyond the cylindrical body portion to form the head *e*, and the opposite end pointed or tapered, as shown at *f*. Each die has its surface made of a form corresponding with one side of the head or face *e* of one pin, and also with the adjoining tapered point of the next pin.

It is to be observed that the grooves *c* are not designed to change the sectional form of the round rod or body, but that they serve merely to guide and present the rods to the dies, which act at the proper points to form the ends of the pin. Thus it is that the rod, in its passage through the grooves *c*, is acted upon only at the portions forming the ends of the pins. Consequently I am permitted to leave the grooves *c* of full width throughout their length, and to locate the surfaces of the dies wholly within the periphery of the rolls. This fact admits of the rolls being reduced in diameter, or shouldered down circumferentially along the sides of the grooves *c*, and of a guide being seated in this reduced portion, as hereinafter explained, without interference with the dies.

In operating the machine, the metal rods are passed between the rolls into the groove *c*. The revolution of the rolls causes the co-operating dies to be brought toward each other against opposite sides of the rod, whereby the dies are caused to divide or nearly divide the rod into lengths suitable for pins, at the same time flattening and expanding the end of one section, so as to form the head of a pin, and tapering the adjacent point of the next section for the next pin. It will thus be seen that each pair of dies serves the threefold purpose of dividing the rod, of heading one pin, and of pointing the next. Each pin having its point formed by one pair of dies has its head formed by the next pair when they in turn operate thereon.

It is obvious that the rolls may be provided each with but a single die, and that a single pin will be produced at each revolution; but as such construction would necessitate the employment of smaller rolls and would limit the capacity of the machine, it is preferred to employ the large rolls represented in the drawings, each with two dies thereon, so that two pins will be produced at each revolution.

In order to afford room for the widened or expanded head formed by the action of the dies, the rolls are recessed or shouldered circumferentially, as shown at *g*, on each side of the groove *c*.

The dies *d* may be constructed each in one or more pieces, dovetailed or otherwise secured

within the rolls, in order that they may be removed when required; or the dies may be made integral with the rolls, the whole being formed in one piece.

5 It is preferred to retain the circumferential recess g , for the reason that such construction admits of the end of the guide F being seated therein, and of the rolls revolving without interference from the guide. This guide 10 consists of a plate secured to the frame or other suitable support in front of the rolls, with one end seated in the groove of the lower roll in position to receive and sustain the rod or pins as they pass from between the 15 rolls.

The guide, which will be grooved or channeled, as indicated in dotted lines in Fig. 2, serves to direct the metal in a right line in 20 the course of its passage between the rolls, thus avoiding the difficulty which would otherwise be encountered, owing to the liability

of the metal to move out of line, and thus issue with the heads and points more fully developed on one side than the other.

What I claim as my invention is—

25

1. In a machine for rolling car-coupling pins, the two co-operating rolls, each provided with a semicircular groove, rabbets or shoulders following the sides of the groove, and a heading and pointing die seated wholly 30 within the periphery of the roll, as described and shown.

2. In a machine for rolling coupling-pins, the two rolls B C , each provided with a semi-circular groove, c , the circumferential recess 35 g , and the die d , as described, in combination with the guide having its end seated in the recesses, as described and shown.

ROBERT RICHARDSON TURNER.
